UNITED STATES PATENT OFFICE.

ROBERT DELL, OF LONDON, ENGLAND, ASSIGNOR, BY MESNE ASSIGNMENTS, TO THE UNION SWITCH & SIGNAL COMPANY, OF SWISSVALE, PENNSYLVANIA, A CORPORATION OF PENNSYLVANIA.

RAILWAY SIGNALING APPARATUS.

Application filed March 7, 1923, Serial No. 623,593, and in Great Britain March 18, 1922.

This invention relates to signaling systems for railways and the like of the kind comprising light signals constituted by electric lamps operated by alternating or pulsating electric currents.

The invention has for its object to provide improved apparatus of this character in which the signal lamps giving a "danger" and "clear" indication respectively are arranged to be rendered operative alternately without interrupting the circuits through which either of these lamps is supplied with operating current.

According to the present invention this action is attained by the provision of a special transformer interposed between the source of supply of current for the signal lamps and the circuits in which these lamps are connected, the transformer being adapted to cause current to be supplied to one or other of the signal lamps by varying the distribution of the magnetic flux within the transformer core.

The invention is illustrated in the accompanying drawings, of which—

Figs. 1, 2 and 3 are diagrammatic views of various forms of special transformer which may be employed showing the connections and general arrangements of the windings thereof.

Referring now to the system shown diagrammatically in Fig. 1 it will be seen that the apparatus consists of a laminated iron core having three limbs A, B and C. Upon the centre limb B a coil of insulated wire D is wound, which coil is connected permanently to the alternating current supply mains P. The current flowing in this coil will induce a flux in the iron core, and considering a particular instant of time, the direction of flux in the cores would be, say upwards in the centre limb B, dividing and part traveling downwards in each of the outer limbs A and C. On the limbs A and C, two coils E and F are wound. These coils will have electro-motive forces induced in them by the flux traversing the cores, and the coils are so connected that the electro-motive forces aid each other thus producing a current through the red lamp N.

Upon the limbs A and C are also wound coils H and J. These coils will also have electro-motive forces induced in them, but they are connected so that the electro-mo-

tive forces are in opposition and thus no current is produced in the green lamp K.

It will be understood that the number of turns in coils H and J must be in inverse ratio to the fluxes in the respective limbs of the transformer in order that the coils H and J may give equal and opposite electro-motive forces under danger conditions.

Upon the limb A a coil L is wound. When the signal is required to show "clear" this coil is energized, for instance, by the action of track relay indicated at O.

Coil L is arranged to produce a flux of the same magnitude as D. Considering the fluxes in the limbs now at a particular instant of time. There will be a flux traveling upward in limb A and another traveling upward in limb B, these combining and returning downward through limb C.

It will be seen that the electro-motive forces induced in coils E and F will now be in opposition, the direction of the electro-motive force in coil E having reversed. There is therefore no current through lamp N. At the same time the electro-motive force in the coil H is also reversed, so that the electro-motive forces in H and J now aid each other and produce a current through lamp K.

The coil M has less turns than L and is connected in opposition with L. This is for the purpose of preventing coil L feeding back on to the line in case of a fault developing in the cable.

Referring now to Fig. 2 a modified arrangement is illustrated in which the coils E, F are provided with extensions Q, R, respectively of their windings, these coil extensions being connected to indication conductors S leading to any suitable type of indication apparatus at a remote point, such, for instance, as a signal cabin.

It will be understood that when the coils E and F are co-operating to transmit current to the signal lamp N a higher electro-motive force will be impressed upon the indication conductors S and thus cause an indication to be given that the lamp N is illuminated.

Referring now to Fig. 3 the invention is illustrated as applied to signal apparatus adapted to give three different indications, this apparatus comprising three signal lamps indicated at W, T and U, respectively.

Two special transformers are employed, each similar to the transformer shown in Fig. 1, and having cores A, B and C, and A', B', C', respectively, and windings D, E, F, etc., and D', E', F', etc., respectively.

The transformer winding D is permanently connected to the supply main P and generates fluxes traversing the cores which induce electro-motive forces in the coils E, F which co-operate to cause current to traverse the danger signal lamp W, the electro-motive forces generated in the coils H, J, opposing one another so that current is not supplied to the coil D' of the second transformer to which the coils H, J are connected. Consequently, the signal lamps T, U which are connected to the coils E', F' and H', J' on the second transformer are both inoperative.

In the event of the track section ahead of the section controlled by the signalling apparatus being unoccupied by a train or vehicle, the coil L is energized by the action of a track relay O, so that the direction of the flux traversing the coils E and H is reversed. The coils E, F, consequently oppose one another and the signal lamp W is extinguished whereas the coils H, J assist one another and current is supplied to the coil D' of the second transformer. The lamp T is therefore illuminated by current from the coils E', F' assisting one another and a caution indication is given.

In the event of the next adjacent track section ahead being also unoccupied the track relay contact V is closed and current is supplied to the coil L'. The direction of the flux traversing the coils E' and H' is thus reversed and the lamp T' is extinguished and current supplied to the lamp U from the coils H', J' which now assist one another, thus giving a safety indication.

The invention is not limited to the particular relative arrangements of the various windings upon the limbs of the transformer core as above described and any equivalent arrangement may obviously be adopted.

Having now particularly described and ascertained the nature of my said invention, and in what manner the same is to be performed, I declare that what I claim is:

1. In combination, a signal comprising electric lamps, a source of alternating current, a transformer interposed between said source and said lamps, and means for varying the distribution of magnetic flux in the core of said transformer to selectively supply current to said lamps.

2. In combination, a signal comprising electric lamps, a source of alternating current, a transformer interposed between said source and said lamps, and having a plurality of magnetic paths in multiple, and means for varying the distribution of magnetic flux in said paths to selectively supply current to said lamps.

3. In combination, a signal comprising electric lamps, a source of alternating current, a transformer energized from said source, a circuit for one lamp including a pair of transformer windings connected in series to oppose each other under the normal condition of flux distribution in said transformer, a circuit for another lamp including a pair of transformer windings connected in series to assist each other under the normal condition of flux distribution in said transformer, and means for varying the distribution of flux in said transformer.

4. In combination, a signal comprising electric lamps, a source of alternating current, a transformer energized from said source, a circuit for one lamp including a pair of transformer windings connected in series to oppose each other under the normal condition of flux distribution in said transformer, a circuit for another lamp including a pair of transformer windings connected in series to assist each other under the normal condition of flux distribution in said transformer, and means for varying the distribution of flux in said transformer.

5. In combination, a signal comprising electric lamps, a source of alternating current, a transformer energized from said source, a circuit for one lamp including a pair of transformer windings connected in series to oppose each other under the normal condition of flux distribution in said transformer, a circuit for another lamp including a pair of transformer windings connected in series to assist each other under the normal condition of flux distribution in said transformer, the windings included in one of said lamp circuits being extended to supply current to an indication circuit, and means for varying the distribution of flux in said transformer.

6. In combination, a signal comprising electric lamps, a magnetizable core comprising three parallel limbs, a primary winding located on the middle limb, a circuit for one lamp including two windings located on the two outer limbs respectively and so connected that the voltages induced therein due to flux created by said primary winding oppose each other, a circuit for another lamp including two windings located on said outer limbs respectively and so connected that the voltages induced therein due to flux created by said primary winding assist each other, and means for varying the distribution of the flux in said outer limbs due to said primary winding.

7. In combination, a signal comprising electric lamps, a magnetizable core comprising three parallel limbs, a primary winding located on the middle limb, a circuit for one

lamp including two windings located on the two outer limbs respectively and so connected that the voltages induced therein due to flux created by said primary winding oppose each other, a circuit for another lamp including two windings located on said outer limbs respectively and so connected that the voltages induced therein due to flux created by said primary winding assist each other, a second primary winding on one of said outer cores arranged to create in such limb a magnetic flux which opposes the flux therein due to the first primary winding, and means for controlling the supply of alternating current to one of said primary windings.

8. In combination, a signal comprising electric lamps, a magnetizable core comprising three parallel limbs, a primary winding located on the middle limb, a circuit for one

lamp including two windings located on the two outer limbs respectively and so connected that the voltages induced therein due to flux created by said primary winding oppose each other, a circuit for another lamp including two windings located on said outer limbs respectively and so connected that the voltages induced therein due to flux created by said primary winding assist each other, a second primary winding on one of said outer cores arranged to create in such limb a magnetic flux which opposes the flux therein due to the first primary winding, and means for constantly supplying alternating current to one of said primary windings and for at times supplying alternating current to the other of said primary windings.

In testimony whereof I affix my signature.

ROBERT DELL.
